UNITED STATES PATENT OFFICE

ANTHONY FULCO, OF LOS ANGELES, CALIFORNIA

SEALING TABLE

Application filed March 21, 1928. Serial No. 263,321.

My invention relates to sealing tables adapted for special use in connection with an article wrapping machine, and more particularly to machines for wrapping bread.

It has been found in practice that the ends of the waxed paper used for wrapping hot bread are not sealed properly, and it is an object of my invention to provide a means whereby the ends of each bread wrapper will be effectively sealed.

While my invention is especially useful in connection with bread wrapping machines, it will be clear that in its broader aspects it is adapted for other uses, and is not in any sense to be limited to such machines.

A further object of my invention is to provide a novel form of sealing table having a flat base and a hinge portion on one end thereof, adapted to be positioned on one of the cross pins or shafts of a suitable framework, the other end having a downwardly bent portion adapted to embrace another cross pin or shaft of said framework, means in the form of one or more springs being associated with one of said pins or shafts and said hinge portion whereby as wrapped articles are moved over said table, said downwardly bent portion will be raised or lowered.

The above and further objects and advantages of my invention, as will hereinafter more fully appear, I attain by the construction described in the specification, and illustrated in the drawings, forming a part of my application.

Reference is had to the accompanying drawings, in which similar reference characters denote similar parts. In the drawings,

Fig. 1 is a fragmentary top plan view of sets of my novel form of wrapper sealing tables associated with the framework of the wrapping machine,

Fig. 2 is a side elevation view of Fig. 1,

Fig. 3 is an enlarged perspective view of one of the sealing tables, with spring removed therefrom,

Fig. 4 is a still further enlarged front elevational view of my sealing table showing the front end thereof engaging one of the

cross pins or shafts of the framework of the wrapping machine,

Fig. 5 is a side elevational view of two of the sealing tables with springs in position, one of said tables being in raised position 55 while the other is in lowered position,

Fig. 6 is a more or less diagrammatic view showing how the sealing tables operate to seal the ends of each wrapper,

Fig. 7 is a similar view, illustrating the 60 conveyers for conveying the articles to be wrapped to the wrapping machine, and

Fig. 8 is an enlarged side elevational view, similar to Fig. 6, but illustrating the heating element.

Describing my invention more in detail, my novel form of sealing table is adapted to be used in connection with a conventional form of wrapping machine, illustrated in Fig. 7 in a more or less fragmentary, diagrammatic manner. Said machine comprises an endless chain or link 8 supported by sprocket wheels 5, positioned above the pressure shoe 6, under which the bread or other articles to be wrapped are passed, 75 fingers 7 being provided to move said bread or articles, the latter being conveyed thereto by means of an elevator, not shown, positioned to the left of Fig. 7, the wrapped and sealed bread being pushed from the sealing 80 tables by said fingers to the fast conveyer 2 and thence to the slow conveyer 9. Since this structure is entirely conventional, further description is not deemed necessary.

My sealing table, designated generally by 85 the numeral 10, comprises a base 12 having a preferably downwardly bent portion 14, cut away as at 16 for a purpose presently to be described, which portion is adapted to embrace loosely one of the cross pins or 90 shafts 15 of the framework F (Figs. 1 and 2) the other end of said base being provided with a hinge portion 18 adapted to engage another cross pin or shaft 20 of said framework.

For the sake of simplicity and ease of construction, the hinge portion 18 is downwardly curved and cut away to provide the extension 22, depending from said hinge portion, which extension is equipped with a 100

hole 24 whereby one end of the spring 26 may be engaged with said extension, the other end of said spring being passed over the pin or shaft 15, the cut away portion 16 being provided to facilitate this purpose. It will, of course, be understood that the exact mounting of said table and said spring are immaterial.

As seen in Fig. 1, any preferred number 10 of such tables may be provided, the cross pins 20 of the hinge portion 18 passing across the framework holding said tables, and anchored thereon as desired, the cross pins 15 also being mounted on said framework 15 work in a similar manner. Moreover, any conventional heating means, such as the electric heating element 11, connected to the electric leads 15, may be positioned under the sealing tables 10, as shown more particularly in Figs. 7 and 8. Although this 20 construction, except in that it enters into the combination with my invention, is entirely conventional, the provision of a heater is immaterial, that feature being common 25 with existing bread wrapping machines.

The operation of my invention should now be clear. As seen in Fig. 7, as the wrapped articles or bread are moved forwardly by the conveyors 9 and 2, with the ends of the 30 wrapped paper unsealed, the tables rise and fall, the base in their raised position effectively sealing said ends together as the bread or articles are conveyed thereover. As the articles reach the tables 10, the fingers 7 35 push said articles under the pressure shoe 6, the sealing being accomplished as just described.

While I have thus described my invention with great particularity, it will be clear that 40 the same may be modified throughout a wide range. I accordingly do not propose to be limited to the exact details of construction shown and described, but reserve the right in practice to make any and all modifications 45 thereof that fall within the scope of the appended claims.

I claim as my invention:

1. A sealing table adapted for special use in connection with an article wrapping machine, comprising a flat base, a hinge portion on one end of said base, an extension depending upon said hinge portion, a downwardly bent pin engaging portion, and spring means associated with said extension 50 and said pin for causing said downwardly bent portion to be raised and lowered on said pin.

2. A sealing table comprising a sealing base, a bifurcated downwardly bent joint portion on one end of said base, a pair of downwardly curved portions on the other end of said base, and an extension depending from said base and positioned between said downwardly curved portions.

3. A sealing table for use in connection

with wrapping machines comprising a flat base, a downwardly curved bifurcated front portion and a pair of downwardly curved rear portions, a tab extending downwardly between said rear portions, a rear pin extending through said rear portions, said front portion being adapted to engage a cross pin of said machine, and a spring connecting said cross pin to said tab.

In testimony whereof I have signed my name to this specification.

ANTHONY FULCO.
